United States Patent Office.

GEORGE WILKINSON, OF PROVIDENCE, RHODE ISLAND, ASSIGNOR TO THE GORHAM MANUFACTURING COMPANY, OF SAME PLACE.

Design No. 2,996, dated April 7, 1868.

DESIGN FOR A FORK OR SPOON-HANDLE CALLED "RUSH."

The Schedule referred to in these Letters Patent and making part of the same.

TO ALL WHOM IT MAY CONCERN: .

Be it known that I, GEORGE WILKINSON, of the city and county of Providence, and State of Rhode Island, have originated a new Design for Articles of Silver, and other metals and plated ware, of which the following is a full, clear, and exact description, reference being had to the accompanying specimens or drawings, making part of this specification; that is to say, for a design called the "Rush," for the handles of spoons, forks, and other table-ware and implements, of which—

Figure 1 is a view of the front side of the said design, and

Figure 2 is a view of the back side of the same—

Similar letters indicating corresponding parts in both the figures.

The said design consists in the peculiar outline, shape, form, or contour of the handle, as represented, as one feature, with ornamental configurations of a peculiar character, as adapted thereto, as another feature of design.

The outline or first feature mentioned, comprises a plain half round stem or shaft, L, upon which is engrafted a wide flat blade, R, which expands into two pointed lobes b b at its extremity, not unlike the tail of a fish. At the point of its junction with the shaft L, the blade is supported with brackets t t, of ornamental scroll-work, and ties or bands s s. The shaft terminates in a husk, d, from which shoot forth the stalks and leaves of rushes in relief upon a frosted groundwork, h, enclosed by a bead or thread in an ornamental figure, the same forming the ornamental feature of the front side, from which the above-mentioned name is derived.

The ornamental feature of the back side consists of a chamfered or bevelled edge upon the blade, with a bead or thread, t, conforming to the outline of the blade, or nearly so, and enclosing, near its junction with the stem or shaft, an ornament of Grecian honeysuckle. This side of the shaft is flat, and is ornamented with a double bead or thread upon each edge, which terminates in an ornament of scroll-work upon the bowl K.

Claim.

I claim the design for the handles of spoons, forks, &c., substantially as herein shown and set forth.
